(57) **CLAIM**

The ornamental design for a combined instrument and charging base for destroying syringe-type needles, as shown and described.

DESCRIPTION

FIG. 1 is a perspective view of the instrument of the combined instrument and charging base for destroying syringe-type needles embodying our design;

FIG. 2 is a top view thereof;

FIG. 3 is a front elevational view thereof;

FIG. 4 is a back elevational view thereof;

FIG. 5 is a left-side elevational view thereof;

FIG. 6 is a right-side elevational view thereof;

FIG. 7 is a bottom view thereof;

FIG. 8 is a perspective view of the charging base for the combined instrument and charging base for destroying syringe-type needles embodying our design;

FIG. 9 is a top view thereof;

FIG. 10 is a front elevational view thereof;

FIG. 11 is a back elevational view thereof;

FIG. 12 is a left-side elevational view thereof;

FIG. 13 is a right-side elevational view thereof;

FIG. 14 is a bottom view thereof;

FIG. 15 is a perspective view of the combined instrument and charging base for destroying syringe-type needles embodying our design;

FIG. 16 is a top view thereof;

FIG. 17 is a front elevational view thereof;

FIG. 18 is a back elevational view thereof;

FIG. 19 is a left-side elevational view thereof;

FIG. 20 is a right-side elevational view thereof; and,

FIG. 21 is a bottom view thereof.
